UNITED STATES PATENT OFFICE.

ERNEST N. JANSON, OF WASHINGTON, DISTRICT OF COLUMBIA.

STEAM-BOILER.

SPECIFICATION forming part of Letters Patent No. 658,110, dated September 18, 1900.

Application filed February 1, 1900. Serial No. 3,644. (No model.)

To all whom it may concern:

Be it known that I, ERNEST N. JANSON, a citizen of the United States, and a resident of the city of Washington, District of Columbia, have invented certain new and useful Improvements in Sectional Water-Tube Boilers, of which the following is a full description, the drawings accompanying forming a part of this specification.

- 10 While in many respects relating to water-tube boilers in general, my invention refers specifically to that water-tube boiler on which Letters Patent of the United States No. 727,754 were granted to me on June 27, 1899.
- 15 In the patent referred to I illustrated and described a sectional boiler, in which my object was to obtain for the water and gases of combustion a circulation as nearly perfect as possible; but although such results in the main 20 have been obtained I am aware that still better results may be gotten with the improvements appended. These improvements are clearly shown on the drawings and fully described in the following specification.
- 25 Experience with water-tube boilers of the type shown has demonstrated that in the lower rows of tubes, due to the intense heat, a violent and rapid conversion of water into steam takes place, rendering said tubes to 30 become overheated and elongated with a permanent set due to excess of the elastic limit in the material. This injurious action is principally caused by the sluggishness in the supply of circulating water through these 35 tubes. In order to counteract the distortioning effects spoken of, I have shown a boiler of identical features as the one described in Letters Patent No. 627,754, but with direct downcomers or downflow-pipes at each end of 40 each drum, as in Figures. I, II, IV, and V, or a number of side downcomers connecting the intermediate pipes 11 and 11' as well as the drums 5 and 5' with the collectors 30 and 31. In Figs. VI and VII said downcomers connect 45 from the middle of each drum to a manifold placed at the lower ends of the lower headers, the manifold or manifolds of each boiler uniting the steam-drum of the opposite boiler. The manifolds so arranged will also serve as 50 blow-off connections. The above-mentioned downcomers will in an efficient way form the necessary supports of the drums, leaving every section of the tubes and headers of each boiler in a suspended state, allowing free movements, caused by expansion or contraction. The lower row of tubes are spaced with a greater central distance to the adjoining row than any other two rows of tubes in order to facilitate placing of the partitions intended to baffle the gases before the uptakes are 60 reached. These partitions or bafflers are specially advantageous when, owing to various circumstances, the height of the boiler is limited and the uptake area for the gases between the generating-tubes is excessive, in 65 this that said gases of combustion are constrained to traverse the full width of the boiler, acting longer and more directly on its efficient heating-surface.
- 70 In the accompanying drawings, Fig. I is a part-vertical section through the center of the boiler as well as a part outside view showing casing and side downcomers. Fig. II is a part-sectional view of Fig. I at a line X X and a part full view showing the outside of 75 the boiler with the casing removed. Fig. VIII is a section along a line X' X', showing the several side downcomers, and Fig. IX is a sectional view of Fig. VIII. This arrangement makes a boiler in which the side downcomers form fire-walls. Figs. IV, V, VI, and VII show modifications in the arrangement of downcomers. In Figs. IV and V the same arrangement exists as in Figs. I and II, with the exception that the independent downflow-pipes 4 and 4', uniting each header to the drum of the opposite steam-generator, are dispensed with and the whole supply of circulating water is conveyed to the headers through the manifolds by means of the side 80 downcomers alone. Figs. VI and VII contain the same general arrangement of headers, generating-tubes, steam-drums, and manifolds as Figs. I, II, IV, and V; but instead of placing downcomers at each end, as shown 85 in Figs. I, II, IV, and V, one larger downcomer is placed at about the middle of each drum, connecting the manifolds of each boiler to the drum of the opposite steam-generator. The independent downflow-pipes 4 and 4', connecting the headers, as previously described, 90 may either be used or dispensed with, Figs. 95 100

VI and VII on the drawings showing them omitted. The last arrangement offers advantages in such a way that by means of a partition wall or walls E' the grate becomes divided up among two or more independent furnaces, the number being in relation to the number of downcomers used. This modification facilitates cleaning fires in one furnace without shutting down the whole boiler. Fig. 10 III illustrates a method of securing the ends of the tubes to both sides of the header with an extension left on the tubes outside of the headers, to which extension the closing-caps T are screwed on securely.

15 In the drawings, 1 1' represent water-tubes which are secured to the headers by expanding them in the holes provided in opposite sides for their reception. Each of the upper headers 2' 2 connects to the drums 5 5' by 20 means of short tubes 3 3', or the headers may be drawn out to form this connection, substituting the short tubes 3 3'. Each lower header 2 2 is joined to the drum of the opposite boiler by means of extensions 4 4' on the header itself or by tubes secured to the headers in a manner shown and described in Letters Patent No. 627,754, or as shown in Fig. VIII. At each end of the drum and at intermediate places, if considered necessary, is placed a 25 connecting-pipe 11 and 11' between the two drums. At the lower end of the lower headers outside manifolds 16 and 16' connect all headers by means of lower tubes extended or short tubes 25. These manifolds are either 30 made continuous in one piece or divided up in two or more pieces in order to allow for a difference in expansion and contraction of the boiler in various parts over the furnace. In Figs. I, II, IV, and V the side downcomers L L and L' L' connect to the ends of the manifolds 16 and 16', and in Figs. VI and VII comparatively larger downcomers connect said manifolds from the middle of the drums 35 5 and 5'. The side downcomers L and L' in Figs. VIII and IX join the drums 5 and 5', as well as the intermediate pipes 11 and 11' with collectors 30 and 31, to which the manifolds 16 and 16' are connected by means of pipes 23 and 24, these downcomers being 40 variably so formed as to constitute substantial supports for carrying the weight of the boiler. In case the manifolds are divided each part is connected by a pipe S. The bafflers 17 and 18 are arranged on top of the 45 lower and upper rows of tubes on which they rest. They extend at the bottom from one side of the furnace to within a distance of the opposite side, leaving an opening large enough for smoke-uptake between the unbaffled tubes 50 60 with a similar arrangement provided for on the top rows of the tubes.

The vertical tubes 6 in Figs. I and II represent air-heating tubes, having for their functions to abstract the heat from the escaping gases. The air-box 19, containing these tubes, is partitioned off, so as to form two heat-boxes, with a connecting-flue 20 at the bottom.

The space between these heat-boxes facilitates cleaning and renewal of the air-heating tubes.

A represents the combustion-chamber, G the grate-bars, and C the ash-pit.

E is some refractory material, and D represents the fire-doors.

B is an ash-pan.

12 is the casing.

In the process of combustion the products of gases rise to the roof of the furnace and afterward enter the openings V, thence ascend among the generating-tubes until retarded by baffle 17. At this stage the whole volume traverses under said baffle to openings V' and then to the uptakes through the heater-tubes 6.

The air-box 19 may by a simple arrangement, such as placing a diaphragm 21 at the one end of the uptake, be made the smoke-box by allowing the gases to pass through the sides of the casing and thence through smoke-flues similar to the air-trunk 7. In this case 9 said gases pass on the outside of the heater-tubes and the air through the same, whence it enters the ash-pit through trunk 13 after first having passed an opening in the side of the casing.

The water circulates from the lower headers 2 2 through the generating-tubes 1 1' to the upper headers 2' 2', and thence through 3 3' into the drums 5 5', and from the drum of each steam-generator directly by means of the down flow-pipes (or extensions on the headers) marked 4 4' and indirectly by means of the downcomers marked L L and L' L' or only through the latter, back to the lower headers of the opposite steam-generator, the indirect circulation having been effected in passing through manifolds 16 and 16'. An adequate supply of circulating water is in that manner provided for.

What I claim as my invention, and desire to secure by Letters Patent, is—

1. In an aggregate steam-generator the combination of two steam-generators, each composed of a steam-drum, water-tubes and single headers arranged in elements, separate downflow-pipes on the outer sides uniting each lower header of each element in each steam-generator with the drum of the opposite steam-generator, a manifold or manifolds located at the lower ends of the lower headers of each steam-generator, said manifolds connecting each lower header in each steam-generator, and downcomers forming communications between the steam and water drum or drums of each steam-generator with the manifold or manifolds of the opposite steam-generator, substantially as and for the purpose set forth.

2. In an aggregate steam-generator the combination of two steam-generators, each composed of a steam drum or drums, water-tubes and single headers arranged in elements, a manifold or manifolds located at the lower ends of the lower headers of each steam-generator,

5 ator, said manifolds connecting each lower header in each steam-generator, and down-comers forming communications between the steam and water drum or drums of each steam-generator with the manifold or manifolds of the opposite steam-generator, substantially as and for the purpose set forth.

3. In an aggregate steam-generator the combination of two steam-generators, each composed of a steam drum or drums, water-tubes and single headers arranged in elements; a manifold or manifolds located outside of and at the lower ends of the lower headers of each steam-generator, short tubes connecting 15 each header in each steam-generator to the manifolds, parting-walls built between the down-comers placed at the front and back of the boiler, said down-comers forming communications between the steam and water drum 20 or drums of each steam-generator with the manifold or manifolds of the opposite steam-generator substantially as and for the purpose set forth.

4. In an aggregate steam-generator the combination of two steam-generators, each composed of a steam-drum, water-tubes and single headers arranged in elements, separate

downflow-pipes on the outer sides uniting each lower header of each element in each steam-generator with the drum of the opposite steam-generator, and an arrangement of 30 bafflers, which constrain the gases of combustion to take defined, horizontal courses across the tubes over the full width of the boiler, substantially as shown and described 35 and for the purpose set forth.

5. In a water-tube boiler composed of steam-drums, water-tubes and separate headers; said tubes and headers being arranged in elements, in which the tubes pass one another in vertical planes, the tubes forming obtuse angles, bafflers resting on the top and bottom rows of said tubes with an open space provided between the said bafflers and the sides of the boiler, the said open space in 40 the bottom baffle being located on the opposite side of the similarly-arranged space in 45 the top baffle, all for the gases to enter and depart during their passage among the tubes, substantially as described.

It is hereby certified that in Letters Patent No. 658,110, granted September 18, 1900, upon the application of Ernest N. Janson, of Washington, District of Columbia, for an improvement in "Steam-Boilers," an error appears in the printed specification requiring correction, as follows: In line 14, page 1, patent number "727,754" should read *627,754*; and that the said Letters Patent should be read with this correction therein that the same may conform to the record of the case in the Patent Office.

Signed, countersigned, and sealed this 16th day of October, A. D., 1900.
